[57] CLAIM

The ornamental design for a lounge chair, as shown and described.

DESCRIPTION

FIG. 1 is a front perspective view of a lounge chair showing my new design in the form of a recliner;

FIG. 2 is a side perspective view thereof; and

FIG. 3 is a rear perspective view thereof.

The side not shown in FIG. 2 is the mirror image of the side shown.

FIG. 3
